(57) **CLAIM**

The ornamental design for a lubricant director for an elevator guide rail, as shown and described.

DESCRIPTION

FIG. 1 is a perspective view of a lubricant director for an elevator guide rail showing our design;

FIG. 2 is a perspective view thereof;

FIG. 3 is a top plan view thereof;

FIG. 4 is a bottom plan view thereof;

FIG. 5 is a left side view thereof;

FIG. 6 is a right side view thereof;

FIG. 7 is a back view thereof; and,

FIG. 8 is a front view thereof.

The broken lines shown in the drawing of FIG. 1 illustrate boundaries of the lubricant director for an elevator guide rail that form no part of the claimed design, as well as environmental structure of an exemplary “T-shaped” elevator guide rail on which the lubricant director may be installed that also form no part of the claimed design. The broken lines shown in drawing FIGS. 2-8 illustrate boundaries of the lubricant director for an elevator guide rail that form no part of the claimed design.

1 Claim, 5 Drawing Sheets
